UNITED STATES PATENT OFFICE.

ERNEST R. KUHLS, OF DAYTON, OHIO, ASSIGNOR TO THE DAYTON ENGINEERING LABORATORIES COMPANY, OF DAYTON, OHIO, A CORPORATION OF OHIO.

DYNAMO FRAME.

Application filed November 18, 1924. Serial No. 750,645.

To all whom it may concern:

Be it known that I, ERNEST R. KUHLS, a citizen of the United States of America, residing at Dayton, county of Montgomery, 5 and State of Ohio, have invented certain new and useful Improvements in Dynamo Frames, of which the following is a full, clear, and exact description.

This invention relates to construction of 10 frames for dynamo electric machines and includes among its objects a method of manufacture of dynamo frames by which the cost of manufacture may be substantially reduced.

15 Other and further objects and advantages of the present invention will be apparent from the following description of a preferred form thereof, reference being made to the accompanying drawings.

20 Fig. 1 of the drawings is a longitudinal sectional view of a dynamo field frame constructed in accordance with the present invention. Figs. 2 and 3 are end views looking in the direction of the arrows 2 and 3, 25 respectively, in Fig. 1. Figs. 4 and 5 are sectional views taken respectively on the lines 4—4 and 5—5 of Fig. 1.

The dynamo frame includes a tubular member 20, which provides the field frame. 30 This frame may be made from sections of iron pipe or may be formed from flat sheet iron into a cylinder having a welded seam. The frame is provided with one or more openings 21, adjacent one end thereof to 35 provide access to the commutator and brushes which are to be supported within the tubular member 20. Heretofore, it has been the practice to turn or grind the interior wall of such tubular members in order 40 to provide a true cylindrical surface against which the pole pieces are bolted, and which provides for the correct location of the end frames laterally with respect to the field frame. The present invention eliminates 45 this expensive machine operation.

Before machining the frame 20 is approximately cylindrical and its end surfaces are only approximately plane and parallel to each other. The tubular member 20 is provided with finished end surfaces 22 and 23 50 which are parallel to each other and at right angles to the approximate axis of the member. Preferably by a broaching operation the interior wall of the member 20 is provided with a plurality of spaced, longitudi-

nal extending, parallel grooves all at right angles to the plane end surfaces 22 and 23. Each groove is defined by a bottom surface 24 and side surfaces 25 and 26. The distance between these side surfaces is slightly 60 greater than the width of the shank of the pole piece 27 which the groove is to receive. The bottom surfaces 24 are cylindrical and coincide with a common cylindrical surface, the axis of which coincides with the axis of 65 the cylinder shaft which the frame is intended to support.

The pole pieces 27 are cut from lengths of specially rolled iron having the desired cross section as shown in Fig. 5. The shank of 70 each pole piece 27 has a cylindrical side surface, conforming with and engaging the groove bottom surface 24. But one screw 28 is necessary to secure each pole piece 27 to the tubular frame member 20, since lateral 75 displacement of the pole piece is prevented by the side surfaces 25 and 26 of the groove which receives the shank of the pole piece. As shown in Fig. 5, pole pieces 27 present pole faces 29 which are equidistant from the 80 common axis of the cylindrical surfaces 24 of the grooves and are therefore equidistant from the axis of the dynamo shaft which is to be supported by the frame.

Against the end surface 22 of member 20 85 there is secured an end frame 30 which includes a plane annular flange 31 adapted to contact with the end surface 22. The end frame 30 includes a tubular extension 32 for receiving a shaft bearing 33, the axis of 90 which is at right angles to the flange 31. In order to locate the bearing 33 centrally of the pole faces 29, the frame 30 is provided with members cooperating with the grooved bottom surfaces 24 for preventing lateral 95 displacement of the frame 30 and for locating the bearing 33 so that its axis will be located parallel to and centrally of the pole faces 29. These locating members are provided by the radially extending projections 100 34 of a disc 35. The edges of these projections 34 are arcuate and are equidistant from a central sleeve portion 36 of the disc 35 which is adapted to receive the shaft bearing 33. The disc 35 is secured to the 105 end frame 30 by rivets 37, which also secure brush brackets 38 and bracket insulation 39 to the end frame 30. The distance between the diametrically opposite edges of the projections 34 is substantially equal to the dis- 110

tance between diametrically opposite portions of the groove bottom surfaces 24. It is therefore apparent that when the frame 30 is secured against the end surface 22 of the member 20 the shaft bearing 33 will be located parallel to and centrally of the faces 29 of the pole pieces 27.

Against the end surface 23 of the tubular frame member 20 there is secured an end frame 40 having a plane annular portion 41 adapted to engage the end surface 23. Centrally thereof the frame 40 supports a sleeve 42 provided with a shaft bearing 43, the axis of which is perpendicular to the portion 41. In order to locate the bearing 43 centrally with respect to the pole faces 29, the frame member 40 is provided with lugs 44 which are cut from and bent away from the main portion of the frame 40. Each lug terminates in an arcuate edge 45 and all the edges 45 are equidistant from the axis of the shaft bearing 43. The diametrical distance between opposite edges 45 is substantially equal to the diametrical distance between opposite groove bottom surfaces 24. Therefore, when the frame 40 is secured against the end surface 23 of the tubular member 20 the axis of the shaft bearing 43 will be located parallel to and centrally of the pole faces 29, and also in alignment with the axis of the shaft bearing 33.

The frames 30 and 40 are secured in position by bolts 50 and nuts 51.

From the foregoing description it is apparent that the cost of manufacture of the dynamo has been materially reduced by reason of the simplicity of construction and by a method of manufacture which eliminates many of the expensive machine operations which heretofore have been performed. As already mentioned, it has been the practice to make the entire interior surfaces of the tubular frame member perfectly cylindrical in order to provide surfaces for locating the end frames and pole pieces. The method disclosed herein provides for machining the interior surfaces of the frame member at only a sufficient number of places to locate the end frames and pole pieces, the remaining portions of the interior of the tubular frame member being unfinished.

Pole pieces formed from sections of specially rolled iron bars have been found satisfactory since these bars can be rolled fairly uniform with respect to cross sectional dimensions. The cylindrical surfaces of these bars are sufficiently exact so that no machine operation is required. The pole pieces are merely cut off from lengths of bar stock and are drilled and tapped to receive the securing screws 28.

The end frames 30 and 40 of the disc are constructed preferably of flat sheet material and can be struck up by suitable punches

and dies into the desired shape very rapidly. These frames are provided with radially extended and strengthening ribs as indicated in Figs. 1 and 2. The bearings 33 and 43 are press fitted within the tubular portions 32 and 36, and the tubular portion 42 respectively.

While the form of embodiment of the present invention as herein disclosed, constitutes a preferred form, it is to be understood that other forms might be adopted, all coming within the scope of the claims which follow.

What I claim is as follows:

1. A dynamo frame comprising in combination a tubular member having parallel end surfaces and interiorly thereof, a plurality of spaced, longitudinally extending parallel locating surfaces at right angles to the end surfaces; a plurality of pole pieces secured to the tubular member, the shank of each pole piece engaging a locating surface, the pole pieces having their faces equidistant from the axis of the shaft to be supported by the frame; and end frames each secured against an end surface of the tubular member and having spaced locating members each terminating in a surface adapted to engage one of the locating surfaces of the tubular member, and each having a shaft bearing so related to the locating members that the shaft bearings will be in alignment and located centrally of the faces of the pole pieces when the end frames are assembled upon the tubular member.

2. A dynamo frame comprising, in combination, a tubular member having parallel end surfaces and, interiorly thereof, a plurality of spaced, longitudinally extending parallel grooves at right angles to the end surfaces having bottom surfaces equidistant from the axis of the shaft which the frame is intended to support; a plurality of identical pole pieces each having a shank bottoming in a groove; and end frames each secured against an end surface of the tubular member and having a shaft bearing at right angles to the end surface and having spaced locating members terminating in surfaces equidistant from the shaft bearing and each adapted to bottom in one of the grooves of the tubular member.

3. A dynamo frame comprising, in combination, a tubular member having parallel end surfaces and interiorly thereof, a plurality of spaced, longitudinally extending parallel grooves at right angles to the end surfaces having cylindrical bottom surfaces equidistant from the axis of the shaft which the frame is intended to support; a plurality of identical pole pieces each having a shank provided with a correspondingly cylindrical surface adapted to bottom in a groove; and end frames each secured against an end surface of the tubular member and

having a shaft bearing at right angles to the end surface and having spaced locating members terminating in cylindrical surfaces equidistant from the shaft bearing at a distance substantially equal to the radius of curvature of the grooves.

4. A dynamo frame comprising, in combination, a tubular member having an approximately cylindrical interior surface provided with parallel grooves having cylindrical bottom surfaces of the same radius of curvature and equidistant from the axis

of the shaft which the frame is intended to support; and end frames each having a shaft bearing and extending radially therefrom a plurality of locating members terminating in locating surfaces having a common radius of curvature centering in the axis of the shaft bearing and substantially the same radius as the curvature of the bottoms of the grooves. 15 20

In testimony whereof I hereto affix my signature.

ERNEST R. KUHLS.
